UNITED STATES PATENT OFFICE.

JOSEPH F. FRANTA, OF MILWAUKEE, WISCONSIN.

PLAITING-MACHINE.

SPECIFICATION forming part of Letters Patent No. 224,285, dated February 10, 1880.

Application filed May 9, 1879.

To all whom it may concern:

Be it known that I, JOSEPH F. FRANTA, of the city of Milwaukee, in the county of Milwaukee and State of Wisconsin, have invented 5 certain new and useful Improvements in Plaiting-Machines; and I do hereby declare the following to be a full, clear, and exact description of the invention, such as will enable others skilled in the art to which it appertains 10 to make and use the same, reference being had to the accompanying drawings, and to letters of reference marked thereon, which form a part of this specification.

Figure 1 of the accompanying drawings represents a top view of my invention. Fig. 2 represents a side view of the same.

My invention relates to improvements in machines for plaiting goods for dress-trimmings; and it consists in a substantial block having a 20 smooth uniform upper surface provided with two series of metallic spring-plates arranged one above the other, with their flat surfaces on a line parallel to the upper surface of the block around which the fabric to be plaited 25 is folded; also, in the peculiar device by which the spring-plates are secured one above the other to the block, all of which is further explained by reference to the accompanying drawings, in which A represents a block of 30 wood or metal. B are the lower series of metallic spring-plates, which are attached nearest to the upper surface of the block. C are the 35 upper series of metallic spring-plates, which are similar in construction, and are attached in like manner to the block above the plates B.

The spring-plates B and C are respectively hinged to the rods D and E, around which rods the ends of the plates are respectively bent, as shown in Fig. 2. F are staples by 40 which the rods D and E, respectively, are secured to the block A, and retained one above another in the position shown, and by which the plates B and C are retained at uniform distances apart upon the rods D and E. H 45 is a rod for securing the front ends of the spring-plates B and C against the surface of the block A upon the fabric to be plaited. G are staples by which the rod H is retained in its proper position. They also serve to keep 50 the front ends of said spring-plates at proper uniform distances apart.

In using my device the spring-plates B and C are all thrown back, in the position shown

by plates C in Fig. 1, when one end of the fabric to be plaited is laid upon the block. 55 Plate B is then brought forward upon the fabric and bent in the position indicated by the dotted line I, so that the front end of the plate may be inserted beneath the rod H. Thus the end of the fabric is retained between the 60 block and the plate B, when the fabric is folded over the plate B, and thus retained by plate C, which is also brought forward upon the fabric thus folded, and its front end inserted likewise beneath the rod H, when the fabric 65 is again laid upon the block and the process thus repeated, as described, until so much of the fabric as requires plaiting is folded around the plates, when a warm sad-iron may be used upon the fabric thus folded, which causes the 70 plaiting to remain more permanently. When the plaiting process is thus completed the rod H is withdrawn and the fabric is readily drawn forward from the spring-plates.

If desirous to make the plaits wider than 75 the spring-plates, or to increase the distance between the plaits, the fabric may be folded around two or more of the spring-plates; or one or more of the plates may be omitted when folding the fabric, and the fabric may be extended across the space to next plate, and thus the plaits made of such width or at such distances apart as may please the taste.

Having thus described my invention, what I claim as new, and desire to secure by Letters Patent, is—

1. In a machine for plaiting cloth and other fabrics, the flat metallic spring-plates B and C, as arranged in two series, one above another, with their broad surfaces parallel with 90 the surface of the block A, in combination with said block, substantially as shown and described.

2. In a machine for plaiting cloth and other fabrics, the device consisting of block A, provided with staples F and G, metallic spring-plates C and D, as secured one above another to the block A by staples F and G, and rods D, E, and H, substantially as described.

In testimony that I claim the foregoing I have hereunto set my hand this 1st day of May, 1879.

JOSEPH F. FRANTA.
